UNITED STATES PATENT OFFICE.

WINFIELD S. MARR, OF HILDRETH, AND JOHN E. NELSON, OF HOLDREGE, NEBRASKA.

NECKTIE-ADJUSTER.

1,230,000.

Specification of Letters Patent. Patented June 12, 1917.

Application filed October 6, 1915. Serial No. 54,391.

To all whom it may concern:

Be it known that we, WINFIELD S. MARR, of Hildreth, in the county of Franklin and State of Nebraska, and JOHN E. NELSON, of Holdrege, in the county of Phelps and State of Nebraska, citizens of the United States, have invented certain new and useful Improvements in Necktie-Adjusters, of which the following is a specification.

One of the principal objects of our invention is to provide an improved necktie adjuster in the nature of a strip of flexible metal having means for securing it within a collar between the folds thereof, the metallic band being fitted at its ends with loops around which the necktie is adapted to be caught, whereby the tie may be readily slipped back and forth to acquire the correct adjustment, and whereby much shorter neckties than now commonly in use, may be used.

A further object of the invention is to provide an improved device of the class described which will be extremely simple, durable, efficient in operation, and inexpensive to manufacture.

With these and other objects in view which will become apparent as the description proceeds, the invention resides in the construction, combination, and arrangement of parts hereinafter more fully described and claimed, and illustrated in the accompanying drawings in which like characters of reference indicate like parts throughout the several figures, of which—

Figure 1 represents a view in perspective of a collar, partly broken away, equipped with a necktie adjuster constructed according to our invention.

Fig. 2 represents a view in perspective of the adjuster removed from the collar.

Fig. 3 represents a view in section taken vertically and transversely on a plane indicated by the line 3—3 of Fig. 1, looking in the direction indicated by the arrows.

In carrying out our invention we provide a flexible band 5, formed preferably of some suitable metal, said band being of a length somewhat less than the circumference of a

collar with which it is to be used. At points 50 spaced from its ends, the band is provided with suitable clasps 6 adapted to engage the inner fold of a collar adjacent its lower edge in the manner shown so as to position the band 5 between the folds of the collar. The 55 ends of band 5 are each provided with a substantially triangular metallic loop 7, the loops being so arranged that one of their apices occurs adjacent the end of the band, whereby when the device is in place in a 60 collar, the outer leg 8 of each loop lies in substantially parallel relation with the analogous leg of the opposite loop, and in a vertical position.

When the device is arranged within a collar in the manner shown in Fig. 1, the loops 7 are disposed adjacent the ends of the collar but are hidden by the folds thereof. In use the device is placed in the collar and a necktie is then passed through one of the 70 loops 7, the collar put in place and buttoned, and the necktie then passed through the opposite loop and drawn and tied in the manner indicated in Fig. 1. If found more convenient the necktie may be passed 75 through the second loop before the front part of the collar is buttoned in place. By the use of a device such as we provide, it will be readily seen that the necktie may be quickly drawn through the loops, in adjusting the tie, without binding, so that the inconveniences ordinarily experienced when a necktie becomes bound in a collar, are done away with. Furthermore neckties of reduced length may be used in connection 85 with this device, and will present an attractive appearance as neckties of greater length.

Although we have described the preferred embodiment of our invention, we may desire 90 to make such changes in the construction, combination, and arrangement of parts thereof, as do not depart from the spirit of the invention and the scope of the appended claim.

We claim:

A necktie adjuster comprising a flexible metallic band having necktie receiving loops

carried at its ends, and clasps carried by the band at points spaced from its ends and adapted to engage the fold of a collar, such clasps being secured to the band at points adjacent the upper ends of the clasps whereby to entirely conceal the adjuster between the folds of the collar and whereby to properly position the loops with respect to the

height of the collar to acquire proper adjustment of the tie knot.

WINFIELD S. MARR.
JOHN E. NELSON.
